UNITED STATES PATENT OFFICE

108,932

DESIGN FOR A BEVERAGE SHAKER

Edward G. De Foe, Oak Park, Ill.

Application January 12, 1938, Serial No. 74,236

Term of patent 14 years

To all whom it may concern:

Be it known that I, Edward G. De Foe, residing at Oak Park, county of Cook, and State of Illinois, a citizen of the United States, have invented a new, original, and ornamental Design for a Beverage Shaker, of which the following is a specification, reference being had to the accompanying drawing forming a part hereof.

The figure is a perspective view of the beverage shaker showing my design.

I claim:

The ornamental design for a beverage shaker substantially as shown.

EDWARD G. DE FOE.
